UNITED STATES PATENT OFFICE.

LEWIS COLLER, OF FLINT, MICHIGAN.

FIRE-ESCAPE.

SPECIFICATION forming part of Letters Patent No. 269,180, dated December 19, 1882.

Application filed September 11, 1882. (No model.)

To all whom it may concern:

Be it known that I, LEWIS COLLER, a citizen of the United States, residing at Flint, in the county of Genesee and State of Michigan, 5 have invented certain new and useful Improvements in Fire-Escapes, of which the following is a full, clear, and exact description.

This invention is in the nature of improvements in the clutch mechanism for releasing 10 and stopping the basket or conveyer, and in the frame-work, and means for and mode of working the fire-escape shown and described in my Letters Patent of the United States No. 261,584, dated July 25, 1882.

15 The invention consists in a fire-escape having a shaft with rope-drums thereon for carrying one or more baskets or conveyers, combined with a clutch mechanism keyed on said shaft, composed of an incased friction-wheel or 20 pulley provided with clutching-arms to hold said pulley against rotation, and with a releasing device arranged with relation to the wheel and the arms, and operated by a rope within reach of the occupant of the conveyer 25 to release the arms and permit a free rotation of the wheel and its shaft to lower the conveyer, said wheel, however, being under control of the releasing device by the frictional contact of the latter therewith to govern the 30 rapidity of revolution of the shaft and wheel, and consequently the velocity of descent of the conveyer.

The invention further consists in supporting 35 the shaft, drums, and clutch mechanism thereon in a frame-work constructed with means for permitting its application to any avenue of escape from a burning building, all as herein-after specifically set forth and claimed.

In the accompanying drawings, forming part 40 hereof, in the several figures of which like parts are similarly designated, Figure 1 is a front elevation of my fire-escape in position for use. Fig. 2 is a perspective view of the apparatus with the ropes and basket removed. Fig. 45 3 is a perspective view of the clutch mechanism with one side of its casing removed and shown to the left in inside face view, and Fig. 4 is a vertical cross-section of the clutch mechanism on a large scale.

50 A is a shaft arranged to be rotated in a frame composed of the parts C and E E, the part

C having hooks D as means for suspending the apparatus. The said shaft may be tubular for lightness' sake. Two (more or less) pairs of heads, B B, are secured to shaft A to constitute rope drums or spools, on which the ropes R R may be so wound as that one such rope will be unwinding as the other is being wound up. These ropes receive and sustain baskets or other conveyers S, say, for illustration, 60 such as shown in my patent before named. Where two baskets are employed one such basket will be ascending while the other is descending in use, the latter forming the power for raising the former, thus facilitating and 65 expediting the escape of persons from a burning building. All of the drums of a shaft may be under the control of a single clutch mechanism; or each drum may have an independent clutch mechanism applied, say, to one of 70 its heads, so as to admit of its separate operation.

The improved clutch mechanism herein shown and described I have invented with special reference to the facilitating the starting, 75 controlling, and stopping of the basket or conveyer in its descent or ascent. The casing is composed of disks I I' and a connecting-rim, F, and pins or bolts P, through which disks the shaft A passes, and within this casing, 80 keyed upon the shaft so as to rotate with it, is a wheel or pulley, G, having two or more internal lugs or teeth, N.

H is a strap, preferably of spring-steel, secured to one of the bolts or pins P, and nearly 85 encircling the rim of the wheel G, and finally extending outside the casing through a slot therein, where an operating-cord, Q, is attached to it. The strap H is held from lateral displacement in the casing by guide flanges or 90 clips O, secured to the inner face of the rim F.

K K are strong springs bolted to the inner faces of the disks I I', and bearing clutch-blocks L. (See details, Fig. 3.) These clutch-blocks L are notched to fit or embrace the 95 opposite edges of the rim of the wheel or pulley G in such manner and to such extent as that as the wheel revolves one of the lugs or teeth N will abut against said blocks to stop the rotation of the wheel.

In order to give the blocks plenty of play and to re-enforce their holding-springs K, I ar-

range them in slots in the casing. (See Figs. 2 and 4.) The blocks L L are disengaged from the lug N by being moved laterally from the wheel by the drawing of the strap H toward the wheel, the edges of said strap coming in contact with beveled ends of the blocks and forcing said blocks away from each other and from the wheel, so as to permit the wheel to rotate. Now, as the strap comes in contact with the rim of the wheel after the disengagement of the blocks and wheel, tension may be applied to said strap to increase or diminish the friction between it and the wheel, to thereby retard (more or less) the rapidity of rotation of the wheel and shaft, and consequently govern the velocity of the descending basket or conveyer. This frictional contact of the strap upon the wheel is exerted through the hand-rope Q, which may extend through the basket or conveyer, so as to be in reach of the occupant for his control; or it may extend through the basket or otherwise to the ground, so as to be operable by the fireman or other authorized person. The greater the pull on the rope the more excessive will be the frictional contact of the strap upon the wheel, and consequently the slower the revolution of the shaft and the less rapid the descent of the conveyer. As soon as the rope Q is free the spring-strap 30 draws away from the wheel and the blocks L automatically resume their connection with one of the lugs N. One is thus enabled to regulate with great nicety the rapidity of the fall of the basket; and this fact constitutes one of the special and chief advantages of my apparatus.

The strap H may be of any suitable material that will contact frictionally with the wheel, and I do not limit the application of my invention to any one kind of strap.

The clutch mechanism may be provided with a re-enforce, M, of metal or other suitable material, to receive the frame-work C.

Now, my invention being constructed substantially as above described, it is used by engaging the sash-frame or other part of a window or other opening in a building with the hooks D, whereby the apparatus is suspended for use. A person may jump into the thus suspended conveyer, but it will not start until the clutch mechanism has been positively released by the operation of the rope Q, and, as just described, the velocity of the descent of the basket is controlled by the tension applied to said rope. As one basket ascends the other, where two are used, descends, and if only one clutch mechanism be used it will control the movement of both simultaneously.

The frame, as herein shown, is made of rod metal bent to shape, and while I regard this as an excellent construction—cheap, durable, and light—I do not limit my invention thereto.

Instead of hooking the apparatus to or in a window, I may employ a rod or rail around a building, from which the apparatus may be suspended and moved from place to place, as

and where desired. Such a rail may be in a molding or the cornice of the house, or may be specially erected for the purpose. The unlocking and locking of the clutch mechanism being performed positively, it is impossible for any accidental descents of the conveyer to occur. Hence my apparatus is specially safe.

I do not limit the application of the combination of my clutching mechanism with the shaft and drums and device to be raised and lowered to a fire-escape, as said combination is of much more general utility.

It will be understood that my fire-escape is portable; but it is quite obvious that it can readily be made a fixture at or in any desirable locality or place in a building.

The rim F is preferably struck up or otherwise formed in one piece with the disk I. I have shown but one lug N; but it is obvious that two or more may be employed. The parts E E of the frame-work, made substantially as shown, serve as guides to prevent the ropes running off the spools in winding up.

What I claim is—

1. A fire-escape having a shaft with a rope-drum thereon for carrying a basket or conveyer, combined with a friction-wheel or pulley keyed on said shaft, provided with lateral clutching-blocks to engage lugs on said pulley to hold said pulley against rotation, and with a releasing device and means to operate it to disengage said blocks from the pulley to permit the rotation of the pulley subject to the retarding incident to the degree of tension applied by the said releasing device upon the rim of the pulley, substantially as set forth.

2. The combination, with the shaft, rope-drums, ropes, and conveyers, of a clutching mechanism composed of a wheel keyed to the shaft, and automatically and normally locked by the engagement of clutching-blocks with lugs on its rim to prevent the rotation of the shaft and drums, and a friction-stop to release said wheel to permit the rotation of it and the shaft and drums under the restriction of the frictional contact of said releasing means upon the rim of the wheel, substantially as and for the purpose described.

3. The clutching mechanism herein shown and described, composed of a friction-wheel, G, keyed to the shaft A to be operated, clutch-blocks L L to grasp said wheel to hold it against rotation, a strap, H, to release said wheel from said blocks to permit it to rotate under a frictionally-restrictive action of said strap, and a casing, I I' F, for the whole, substantially as and for the purpose set forth.

4. The shaft A and drums and ropes thereon, conveyers attached to said ropes, friction-wheel G, keyed to said shaft and provided with a lug, N, clutch-blocks L, normally engaging said lug, a friction-strap, H, for releasing said blocks from engagement with the lug, and a rope or cord to operate said strap, and after causing it to release the wheel to impart a retarding effect to the wheel by virtue of frictional

contact therewith, substantially as shown and described.

5. The shaft A, drum-heads B B thereon, clutching mechanism, and the framing C E E 5 and suspending-hooks D, substantially as shown and described.

6. The framing C E E, suspending-hooks D D therefor, the shaft A, borne in said frame, the ropes R R on said shaft between the heads 10 B B, the conveyers S, and the clutching mechanism for starting, controlling, and stopping the

operation of the shaft, the whole constituting a portable fire-escape, substantially as shown and described.

In testimony whereof I have hereunto set 15 my hand this 8th day of September, A. D. 1882.

LEWIS COLLER.
